MESSAGE DISPATCHER FOR RAILROADS

George W. North, Boyceville, Wis.

Application October 7, 1942, Serial No. 461,087

4 Claims. (Cl. 258—24)

This invention relates to railway message dispatchers of a type also known as train order holders.

In most instances train orders are delivered by station agents to various members of train crews as the train is passing a station by attaching the orders to light wooden hoops which have straight handles extending tangentially therefrom. It is customary for the station agent to stand close to the track and reach out with the hoop so that it can be grasped by a member of the train crew. This practice is extremely dangerous since the agent is likely to be struck by pieces of coal falling from the tender and at night he might be struck by a board or other piece of material extending out from a car farther than it should. It is also necessary that the agent be standing in readiness to hand up the order at the exact time the train is passing and even though railroads are operated on schedules, the trains are not always on time. Thus considerable time is wasted which might be devoted to more productivity.

While numerous other train order dispatchers have been previously devised they have been found to either grip the order hoop too tightly thus making it difficult to disengage or they grip the hoop so loosely that it might accidentally become disengaged by the wind.

It is a general object of my invention to provide a train message dispatcher which will hold one or more hoops so that they will be conveniently and properly supported in a proper manner to be grasped by a trainman but at the same time will nicely and easily release the hoop.

A more specific object of the invention is to provide a train message dispatcher which is made up of a number of sections which are relatively freely yieldable in different directions so that when the hoop is grasped by the trainman the support for the hoop can be made to give in nearly any direction.

A further object of the invention is to provide a train message dispatcher which has improved hoop grasping jaws which satisfactorily retain the hoop but which swing open freely when the hoop is pulled.

These and other objects and advantages of the invention will more fully appear from the following description made in connection with the accompanying drawings, wherein like reference characters refer to the same parts throughout the views, and, in which:

Fig. 1 is a side elevation of my invention with

the supporting arms raised to a horizontal position;

Fig. 2 is a front view with the arms lowered;

Fig. 3 is a top plan of the outer portion of an arm;

Fig. 4 is a side elevation of that portion of the arm shown in Fig. 3; and

Fig. 5 is an end view of the outer end of an arm.

- 10 The main support of the apparatus is a post 6 which may conveniently be embedded in a block of concrete 7. Mounted on the post 6 are three arms 8, 9 and 10. The lower arm 8 at its inner end is provided on one side with a strap 11 and on the other side with an angle iron 12. The strap and angle iron 11 and 12 extend rearwardly past the end of the arm 8 and are pivotally connected to the post 6 by means of a pivot bolt 13. The angle iron 12 is provided to lend rigidity 20 to the pivot joint and said angle iron 12 and strap iron 11 are bent downwardly at an angle, as shown in Fig. 1. This permits the arm 8 to swing from the horizontal position of Fig. 1 to a downwardly hanging position, as indicated in 25 Fig. 2. The arm 9 is provided with a similar pivot joint generally indicated at 14, said pivotal connection 14 being connected to a main supporting post portion 15 which extends laterally thence downwardly from the top of the main post 6. The arm 10 is provided with a pivotal connection 16 similar to the ones previously described and in turn is connected to a supporting post portion 17 which extends laterally and thence downwardly on the opposite side of the 30 main post 6. The auxiliary post portion 15 is somewhat longer than said post portion 17 so that when the arms are swung up to the horizontal positions shown in Fig. 1 said arms 8, 9 and 10 will be located at different levels.
- 35 40 45 The extending rear ends of the strap irons 11 and angle irons 12 are connected to ropes or cables 18 which extend downwardly to a reel 19 turned by a hand crank 20. By rotation of the reel 19 the arms 8, 9 and 10 can be raised and lowered.

Figs. 3, 4 and 5 illustrate in detail the construction of the outer ends of the three arms. In Fig. 3 there is indicated the extreme outer end of the arm 8 although, of course, the structure is identical in the three arms. Extending outwardly beyond the end of said arm 8 is a pair of straps 21 which is secured to the ends of said arms 8 by means of suitable screws 22. Each of the straps 21 is notched as at 23 to receive a bolt 24 having nutted ends. The bolt 24 has a

pair of flanges 25 which are positioned just inside the inner faces of the straps 21 as best illustrated in Fig. 3, but are spaced slightly therefrom. Said bolt 24 is made in two halves, one-half of which is adapted to telescope into the other, as shown at 26. Nuts 27 on the ends of the bolt 24 draw the straps 21 against the flanges 28 to secure the bolt to said flanges.

The bolt 24 passes through the inner end of an arm 29 which forms an extension of the arm 8 and, of course, the arms 9 and 10 in each unit of the structure. Between the sides of the extension arm 29 and the flanges 28 are coil springs 30 which have oppositely extending ends 31 and 32. The spring ends 31 are bent inwardly, as shown in Fig. 3, and adapted to be fitted into any one of a series of sockets 33 arranged on an arc in opposite sides of the extension arm 29 and the spring ends 32 are adapted to similarly fit into holes 34 formed in the metal plates 21. Obviously different locations of the spring ends 31 and 32 in any of their respective sockets or holes will change the tensions of the coil springs 30. This spring pivot permits the extension arms 29 to swing yieldably up and down, but the springs 30 are of sufficient strength to normally hold the extension arm 29 in alignment with its respective main arm 8, 9 or 10.

On the outer end of the extension arm 29 is a train order supporting arm 35, which is supported on a pivot bolt 36 which extends through arms 29 and 35 vertically and the train order supporting arm 35 rests upon a suitable bearing member 37. Extending inwardly from the outer or left-hand end of the arm 35 is a bore 38 which is adapted to receive the straight handle portion of a train order hoop such as the hoops 39 shown in Fig. 1.

Secured to the train order supporting arm 35 is a pair of leaf springs 40 which are secured at their rear ends, as shown in Fig. 4, and are free to move at their left-hand or outer ends. A pair of tension springs 41 connect the leaf springs 40 and assist in normally urging them toward each other. Pivotally mounted or hinged to the outer ends of said leaf springs 40 is a pair of jaw members 42, the hinges being indicated at 43. On each of the jaws 42 is a hoop gripping block 44 which is provided with a convex chamfer 45 as shown in Figs. 4 and 5. A pair of stop members 46 limit the extent of movement of the leaf springs toward each other and, of course, similarly limit the movement of jaws 42 and blocks 44 toward each other.

A pair of tension springs 47 are connected between a plate 48 on the rear end of the train order supporting arm 45 and a bracket 49 on the extension arm 29. These springs 47 permit yielding pivotal movement of the train order supporting arm 35 relative to the extension arm 29.

Mounted on each of the arm extensions 29 is a light fixture 50 which is arranged to direct its beam outwardly to illuminate the hoops 39 so that they can be readily seen at night. The lights 50 may be supplied with electricity through a cable indicated at 51.

The apparatus is, of course, adapted to be installed adjacent a railway track at a station and so located that when the arms 8, 9 and 10 are extended as in Fig. 1 the hoops 39 will be in a convenient position to be grasped by the trainman. When a hoop is grabbed its supporting arm 35 will swing in the direction of movement of the train and if it is pulled the jaws 42 will

swing open while the leaf springs 40 separate slightly and the handle of the hoop will slip easily from the socket or bore 38. Should the trainman pull up or down as he grasps and pulls the hoop the arm extension 29 will yieldably tip up or down in the direction of pull and, consequently, the hoop cannot possibly jam to prevent its removal or to injure the trainmen.

In the drawings there are illustrated three 10 arm assemblies. For example, if there are two engines in a train the upper arm assembly could be used for a message to be dispatched to the first engineer, the middle arm assembly could be used for a message to be dispatched to the 15 engineer of the second engine, and the lower unit could be used for a message to the brakeman or other trainman in the caboose.

From the foregoing description it will be seen 20 that I have provided a railway message dispatcher assembly which is so constructed that the hoop carrying the message will always quickly and easily slip from the device and that while several portions of the arm assembly are easily movable out of their arm position they will 25 return to their proper position as soon as the hoop has been released. The mechanism is simple in construction and is so formed that the ordinary strains imposed upon it will in no way injure it. It is simple to load and easily operated. Its cost 30 is not great. It is adapted to save time on the part of the station agent as well as to eliminate danger of injury such as has been outlined above.

It will, of course, be understood that various 35 changes may be made in the form, details, arrangement and proportions of the various parts without departing from the scope of my invention.

What is claimed is:

40 1. In a railway message dispatcher, an upright, a plurality of arms connected to said upright on horizontal pivots, each of said arms having a resilient joint intermediate its ends to provide inner and outer sections, said sections being normally held in alignment by said resilient joint, an extension connected to each outer section by a vertical pivot and held yieldably in alignment therewith, said extension having a longitudinal bore therein extending inwardly 45 from the outer end thereof to receive the straight portion of a train order hoop, and yieldable jaw members adjacent the outer end of said bore to yieldably grip the train order hoop.

50 2. In a railway message dispatcher, an upright, an arm pivotally connected to said upright and adapted to swing relative to said upright to a horizontal position, the outer end of said arm having a longitudinal bore therein to receive the straight portion of a train order hoop, and a pair of jaw members supported at the outer 55 end of said arm adjacent the end of said bore, said jaw members being movable away from each other on lines substantially normal to said arms and also being movable outwardly from the outer end of said arm.

60 3. In a railway message dispatcher, an arm adapted to be extended outwardly in a generally horizontal position, said arm having a socket 65 extending in from its outer end to receive a straight portion of a train order hoop, a pair of yieldable elements at opposite sides of said arm normally tending to spring towards said arm, said yieldable elements having jaw members mounted thereon for pivotal movement relative 70 thereto, and said jaw members being positioned 75

at the open end of said socket and at the outer end of said arm.

4. In a railway message dispatcher, an arm adapted to be extended outwardly in a generally horizontal position, said arm having means at its outer end for engaging a portion of a mail order hoop, a pair of yieldable elements at opposite sides of said arm adjacent said hoop en-

gaging means and normally tending to spring toward said arm, said yieldable elements having jaw members mounted thereon for pivotal movement relative thereto, and said jaw members being positioned outwardly from said outer end of said arm.

GEORGE W. NORTH.
